UNITED STATES PATENT OFFICE.

LOUIS B. SORENSEN, OF NEW ORLEANS, LOUISIANA, ASSIGNOR TO UNITED ANCIENT ORDER OF DRUIDS, OF NEW ORLEANS, LOUISIANA.

DESIGN FOR A BADGE.

43,207.

Specification for Design. Patented Oct. 29, 1912.

Application filed August 9, 1912. Serial No. 714,311. Term of patent 14 years.

To all whom it may concern:

Be it known that I, LOUIS B. SORENSEN, a citizen of the United States, residing at New Orleans, in the parish of Orleans and State of Louisiana, have invented a new, original, and ornamental Design for Badges, of which the following is a specification, reference being had to the accompanying drawing, forming a part thereof.

The figure is a plan view of a badge, showing my new design.

I claim:

The ornamental design for a badge, as shown.

LOUIS B. SORENSEN.

Witnesses:

ISABELLA HAGAN,
A. MANGPANEO.
